UNITED STATES PATENT OFFICE.

JOHN F. SCHULHOFF, OF NEW BREMEN, OHIO.

SAFE.

SPECIFICATION forming part of Letters Patent No. 499,257, dated June 13, 1893.

Application filed January 17, 1893. Serial No. 458,706. (No model.)

To all whom it may concern:

Be it known that I, JOHN F. SCHULHOFF, a citizen of the United States, residing at New Bremen, county of Auglaize, State of Ohio, 5 have invented certain new and useful Improvements in Burglar-Proof Safes, of which the following is a specification.

My invention relates more particularly to improvements in the lock-mechanism of bank 10 and other safes for the security of valuables, and is designed to prevent ingress to the lock-mechanism in the event of any one of the spindles thereof being forced in or withdrawn as is ordinarily done; and it consists in the 15 peculiar formation of the spindle along its shank so as to render its removal impossible, and, in a locking device for such spindle, whereby it is fixedly held in place until it is desired to remove it from within; and, it also 20 consists in the weakening of the spindle at a point close up to the exterior wall of the safe so that it must be easily snapped off at that place should any violence be exerted in attempting to gain access to the safe.

25 It further consists of other details of improvement all of which will be more fully herein set forth.

Referring to the drawings forming a part 30 of this specification, Figure 1, represents a rear elevation of the lock case: Fig. 2, is a vertical longitudinal section on the line $x-x$ of Fig. 3, showing the spindle locking-plates. Fig. 3, is a transverse section on the line $y-y$ of Fig. 1 showing the spindles and the enlargements thereon, and Fig. 4 is a detail 35 showing a spindle from which the knob or dial plate has been forcibly severed.

In the drawings A, represents the lock case, in which are located the spindles B, and their 40 locking slides.

B', represents the enlarged portions of the spindles which in this instance are solid, so as to admit of no play against the inner walls of the case, and which have their extremities b, 45 b, reduced as shown, the outer one of course being for the engagement of the knob or dial plate.

C, represents the locking plates which hold the spindles to their work, once they are in 50 position. These plates are located in cham-

bers F, and are made to fit snugly therein so that they may be made to move to and from the spindles and engage them through the slots c, and at their inner ends. The locking plates are tapped at c', and screws d, having washers d', thereon permit of their adjustment by means of the slots D, in the rear plate of the lock case. It will be perceived that each screw d, on being loosened permits the locking plate to move freely in the chamber F, 60 and when they are moved laterally so that the slots straddle the spindles the screws are turned home and thus lock the plates against any displacement, the spindles of course being free to rotate but having no endwise movement because the shoulders bear against the front plate of the case and the locking plates respectively.

At E, on the spindle will be perceived a ring or depression such as is termed "marking" 70 in shop parlance, preparatory to the severing of a bar of iron. The object of this "marking" is to so weaken the spindle at the wall of the safe as to render it easily breakable, and if any violence is attempted in an effort 75 to force the lock mechanism the spindle will break short off, and thus leave no opportunity for the lock mechanism to be picked or blown as the broken end of the spindle will be flush with the face of the safe, and the enlargements on the spindles, within the casing will prevent their being driven inward. Thus it will be perceived that the spindle cannot be withdrawn or expelled and would be impossible as the spindle would only move with the 80 drill, and it would be too short to grasp.

In Fig. 4, of the drawings I have shown the remainder of the spindle and it is a slot e' which can only be made by bringing this part to an intense heat and making the depression 90 or slot therein with a cold chisel so that one acquainted with the combination may insert an implement therein and open the safe.

It will be understood that I do not limit myself to a solid integral spindle, as collars thereon or openings therein through which pins are passed are equivalents of what I have shown and described.

Changes and modifications will suggest themselves in the device as shown and de- 95 100

scribed which changes are not thought necessary to detail here.

Having thus described my invention, what I claim as new, and desire to secure by Letters Patent, is—

- 5 1. A spindle for safe and other locks, having an annular weakened portion exterior to the face of the safe, and separable at that point when force is applied to the same.
- 10 2. A spindle for safe and other locks having a central cylindrical enlargement, a tubular casing inclosing the same, the said shaft having reduced bearing ends, one of which extends through the outer wall of the safe,
- 15 3. for engaging the knob, the opposite one passing through a rear casing or pocket, in combination with a bifurcated plate located in said pocket the legs of which sit astride this end of the shaft, and adjusting screws tapped
- 20 4. into said plates and extending through slots in the inner walls of the safe for adjusting

and securing said bifurcated plates in position.

3. In combination, a slotted locking plate, a case in which it slides, clamping screws engaging said locking plate and a fixed case plate having slots therein through which said screws pass for adjusting and locking said plate upon a spindle journal.

4. In combination, a spindle having a central longitudinal enlargement and reduced journals, a slotted locking plate for engaging said journals, a casing for said locking plate and set screws for locking said plate to the rear case plate of the lock.

In testimony whereof I affix my signature in presence of two witnesses.

JOHN F. SCHULHOFF.
